UNITED STATES PATENT OFFICE.

JAMES PARTEE, OF SANTA CRUZ, CALIFORNIA.

CONCRETE BUILDING STRUCTURE.

1,423,779.

Specification of Letters Patent. Patented July 25, 1922.

Application filed January 25, 1921. Serial No. 439,821.

To all whom it may concern:

Be it known that I, JAMES PARTEE, a citizen of the United States, residing at Santa Cruz, in the county of Santa Cruz and State 5 of California, have invented a new and useful Improvement in Concrete Building Structures, of which the following is a specification.

My invention relates to improvements in 10 the construction of concrete houses, barns, silos, ships and all building constructions, wherein a framework is provided with a network of reinforcing wires and a metallic reticulum adapted to receive and retain 15 a filling of concrete to form an enclosing structure.

The primary object of my invention is to 20 provide a framing structure adapted to receive and support a concrete filling. Another object of my invention is to provide 25 a durable concrete structure of the class described of simplified and economical construction.

A further object is to provide improved 30 reinforcing means for strengthening a concrete structure.

A still further object of my invention is to provide means for facilitating the provision 35 of doors and windows in a housing structure of the character specified.

I accomplish these and other objects by means of the device disclosed in the drawings forming a part of the specification wherein like characters of reference are used 40 to designate similar parts throughout said specification and drawings, and in which:—

Figure 1 is a transverse sectional view of my improved concrete house construction; Figure 2 is a plan view of the house 45 closed in Figure 1, partly in section along the line 2—2 of Figure 1, parts being broken away to disclose my novel construction;

Figure 3 is an enlarged section disclosing the manner in which door and window 50 frames and casings are set in;

Figure 4 is an enlarged detail of the manner in which the angle iron frame members are joined;

Figure 5 is an enlarged detail disclosing 55 my improved reinforcing network and concrete retaining reticulum as applied to the framework and

Figure 6 is an enlarged section view disclosing my concrete wall and floor construction.

Referring to the drawings the numeral (1) is used to designate a concrete filling applied to a reticulum (2) secured to angle iron members (3) arranged to form the skeleton framework of a house. The reticulum (2) is of metallic construction such as close mesh screen or metal lathing adapted to receive and retain thereon a heavy coating of concrete, to form a floor (4), walls (6), ceiling (7), roof (8) and partitions (9) for a house.

Wires (11) are stretched longitudinally and transversely between adjacent members (3) of the framework in interweaving relation to form a network for reinforcement 70 of concrete (1) applied thereabout. The ends of the wires (11) are twisted about an angle iron frame member (3) and the wires stretched taut as best illustrated in Figure 3 of the drawings, thereby preventing any 75 bowing of the frame work and distributing the weight of concrete uniformly along the entire length of the members (3).

Openings (12) are provided in the reticulum (2) and the reinforcing wires (11) to 80 permit door and window frames (14) to be set into the framework. The door and window frames (14) are molded from concrete in the desired shape and size and are permanently secured in place by the cement 85 filling (1) applied thereabout. Suitable casings (16) are mounted within the frames (14) to receive suitable doors and windows after completion of the walls (6), and partitions (9).

In constructing my improved concrete house or other structure a skeleton framework is built up from angle iron members (3) along any desired plan and the reinforcing network of wires (11) stretched 90 thereon and the metallic reticula (2) secured in position. The door and window frames (14) are then set into the openings (12) provided therefor. A plastic concrete mixture is then plastered or otherwise suitably 100 applied to the metallic reticula in such a manner as to cause the framework, reinforcing network, and reticula to be entirely embedded therein. In this manner a substantial and strongly reinforced concrete 105 shell is erected to form walls (6), ceiling (7), roof (8) and partitions (9). The floor (4) may be formed from a similar concrete mixture, but in my present practice I prefer to use an artificial stone consisting of saw- 110

dust and (or) wood pulp, chalk rock and magnesite mixed in any suitable proportions, laid in a similar manner upon the reticula and reinforcing network and secured to the members (3), provided as joists. The inside of the walls including the partitions and the inside of the roof may be made of this artificial stone mixture.

In this manner I obtain a concrete structure of rigid and durable nature adapted to be constructed with a minimum of expense and labor, to which any suitable finish may be applied for the interior and exterior decoration.

I may also use this method in producing such structures as bath-tubs, mantels, troughs and the like.

Having thus described my invention what

I claim as new and desire to secure by Letters Patent is:—

A concrete structure comprising a metallic frame work, reinforcing wires arranged in net formation so that its members are substantially parallel to the members of the frame work and a metallic reticulum stretched between adjacent members of the frame work allowing door and window openings to be cut into the same, concrete applied to said reticulum and embedding the reinforcing wires to form the walls, floor and roof of the structure, and door and window frames molded from concrete and secured in the openings provided therefor to receive suitable door and window casings.

JAMES PARTEE.
